UNITED STATES PATENT OFFICE

2,569,933

BUCKLE

Robert W. Johnson, Chicago, Ill.

Application March 18, 1948, Serial No. 15,700

1 Claim. (Cl. 24—197)

1

My invention relates to buckles for garments, and more particularly to the type applied to belts, scarves, laces, etc., and one object is to provide a buckle which presents an attractive appearance while forming an efficient securing device. A further object is to provide a buckle which combines a pair of units of well known design in a manner to form an efficient securing device.

Another object is to provide a buckle which needs no mechanical contrivances to accomplish its purpose, presenting only an ornamental appearance.

An additional object is to design the buckle along lines of extreme simplicity and neatness.

With the above objects in view, and any others which may suggest themselves from the description to follow, a better understanding of the invention may be had by reference to the accompanying drawing, in which:

Fig. 1 is a perspective view of a typical belt, partly broken away, and carrying the preferred form of the buckle at the front;

Fig. 2 is a section on the line 2—2 of Fig. 1;

Fig. 3 is an elevation showing one modification;

Fig. 4 is a back view of the showing in Fig. 3;

Fig. 5 is a section on the line 5—5 of Fig. 3;

Fig. 6 is an elevation of a further modification as applied to a scarf or kerchief; and

Fig. 7 is a section on the line 7—7 of Fig. 6.

In accordance with the foregoing, reference to Fig. 1 indicates a strap type of belt at 10. Usually, a buckle is secured to one end of such a belt, while the other end is formed either plain or with a row of holes for engagement in the buckle. In the present instance, however, the ends of the belt do not receive any device or perforation, but are left plain.

Fig. 1 shows one form of the buckle made up of a frontal loop 11 and a ring 12 in back of the same. The loop 11 is rectangular in form and with its length vertically directed. Thus, the loop is of sufficient length to lie against the upper and lower portions of the ring 12; and the loop has a narrow central bar 13 in addition to its regular side bars 14. The ring 12 is plain. Both the loop and the ring are of familiar design and made of flat stock, the material preferably being plastic.

As shown in Fig. 1, the application of each end portion 15 of the belt 10 to the assembly of the loop 11 and ring 12 is first by directing the belt section inwardly behind the correspondingly-located loop bar 14. The belt section is then trained forwardly through the related opening in the loop

2 with a return fold 16, which is then directed rearwardly to thread through the space between the bar 14 and the corresponding side of the ring 12, finally issuing in an outward direction from the buckle as shown.

Primarily, the end sections of the belt applied as stated make a balanced connection with the buckle, securing engagement in the same by means of the side portions of the ring 12. However, the connection is strengthened when expansive stresses are imposed on the belt. In this event, the first action of the belt is to tug on the fold 16 with a tendency to pull the loop bars 14 outwardly. This tendency causes the return folds to be compressed between the side bar 14 and the corresponding side of the ring 12, to the end that the belt becomes more firmly attached to the buckle. Also, in case the pressure on the belt is relaxed, the buckle will not loosen, since the loop 11 is retained in the fold 16; and the shoulders 15a of the belt portions 15 prevent the ring from shifting laterally. A retentive connection is thus had between the belt and the buckle through the use of two members which are separate, yet require no hinges, fittings or means other than the belt to keep them together. Thus, no mechanical contrivance is noted on the buckle, and the same appears to all intents and purposes as an attractive ornament, while serving its purpose efficiently and along sound mechanical principles.

The modification of Figs. 3 to 5 employs a pair of units 20 and 21 similar to the loop 11. However, the unit 20 is of sufficient width to accommodate two internal bars 22, and these are employed for the folding of the belt sections. In this case the unit 21 is in the form of a rectangular ring to match the unit 20. Therefore the buckle presents only one unit when viewed from the front, indicating compactness and simplicity.

The modification of Figs. 6 and 7 is more or less a composite of the first and second forms of the invention. Thus, the original circular ring 12 is used in the rear. However, twin loops 25 and 27 are used side by side in front of the ring, such loops having medial bars 27. Also, the loop openings outside these bars are shorter than on the inner sides, as indicated at 27a. Thus, each end portion 28 of the scarf or kerchief 29 illustrated is threaded from the rear around the corresponding bar 27 to make a return fold 30 into the related side 31 of the ring, the section continuing outwardly along the back of the same to issue as shown. The modification just described is an attractive departure from single loop buckles; and it enables each loop to be

applied and adjusted independently in relation to the ring, without pulling on or in any way affecting the adjustment of the companion loop.

It is now apparent that the novel buckle is an accessory which is primarily of an independent character, requiring no original connection with the belt, scarf or other article which it may serve. The buckle is entirely contained in the two—or three—members which assemble to receive the end portions of the belt, scarf or like article. Yet, the particular application of the belt portions to the members of the buckle causes these to coact with a clamping effect on the belt which is strengthened in proportion with the expansive stresses imposed on the same. A buckle 15 is thus had which is easily produced and applied, operates efficiently along any portion of the belt without extra securing devices, presents a neat and attractive appearance, and is of a nature to be formed with any number of designs.

While I have described the various forms of the invention along specific lines, various minor changes or refinements may be made therein without departing from its principle, and I reserve the right to employ all such changes and refinements as may come within the scope and spirit of the appended claim.

I claim:

A buckle for garment belts or the like whose terminal sections gather from the sides in spaced relation, comprising a rigid ring with side portions in front of said terminal sections, and a pair of rigid loops disposed in laterally arranged relation in front of said ring, each loop having

an internal bar spaced inwardly from said side portions, each of said terminal sections being trained forwardly along the inner edge of the related bar to wrap over the same and to the rear, and then passed outwardly behind the related one of said side portions to issue from the same as one end of the belt, the internal bar of each loop defining a slot on the inner side and defining a shorter slot on the outer side, and the outer edge of the internal bar intercepting a relatively short segment by crossing part of the inner edge of the corresponding side portion of the rigid ring and thereby constricting the passage of the corresponding terminal section to the rear.
